COLUMBIA PLANOGRAPH CO., WASHINGTON, D. C.

UNITED STATES PATENT OFFICE.

JOHN OERTLY, OF CINCINNATI, OHIO, ASSIGNOR, BY MESNE ASSIGNMENTS, TO NEW JERSEY PATENT COMPANY, OF WEST ORANGE, NEW JERSEY, A CORPORATION OF NEW JERSEY.

KINETOSCOPE.

1,093,646.

Specification of Letters Patent. Patented Apr. 21, 1914.

Application filed April 24, 1906. Serial No. 710,698.

To all whom it may concern:

Be it known that I, JOHN OERTLY, a citizen of the United States, residing at Cincinnati, in the county of Hamilton and State of Ohio, have invented certain new and useful Improvements in Kinetoscopes, of which the following is a description.

My invention relates to kinetoscopes or apparatus for the projection of moving pictures, and more particularly to the provision of means for cutting off the projecting light from the film when the latter is stationary, so that it will be impossible for the film to be ignited from this cause. Heretofore movable shutters have been used for this purpose, said shutters being controlled by a centrifugal governor operated by the film driving mechanism. Such devices are, however, more or less complicated and expensive to manufacture and cannot be applied to standard machines now in general use so readily as the invention herein disclosed.

My invention has for its object the provision of a shutter and controlling means operating by friction and comprising a minimum number of parts, so that the device will be cheap to manufacture and reliable and certain in operation.

A further object is the designing of parts so that the device can be very readily applied as an attachment to kinetoscopes now in general use.

With these ends in view my invention consists in the features hereinafter described and claimed.

Reference is hereby made to the accompanying drawings of which—

Figure 1 is a rear elevation showing in dotted lines a projecting machine of the Edison type, with one form of my invention, in full lines, applied thereto. Fig. 2 is a side elevation of Fig. 1, the shutter occupying an open position, as when a film is being exhibited by the apparatus. Fig. 3 is a similar view showing the shutter in a closed position, as when the parts are at rest. Fig. 4 is an isometric view showing the frames which carry the film driving mechanism and display opening respectively and the means by which my invention may be applied to said first frame. Fig. 5 is a detail

section of the frictional, shutter-controlling mechanism, on line 5—5 of Fig. 2. Figs. 6 and 7 are detail views of the same.

In all of the views corresponding parts are designated by the same reference numerals.

In the apparatus shown, the kinetoscope comprises the usual main support *a* which carries the frame *b* in which are mounted the usual gears and sprockets for driving the film past the display opening *c* which is formed in the plate *d*, supported from the body *a* in the usual manner. The frame *b* is provided with the usual vertical pin *e* upon which is hinged the gate *f* which is adapted to be opened as shown in Fig. 4 in order to allow the film to be threaded through the apparatus, after which it is closed and locked by the latch *g* to hold the film in proper position with respect to the display opening *c*.

The improved attachment, as shown, is composed of two members, namely: a shutter frame 1 and a shutter controlling device 2. The shutter frame 1 is provided with a pair of laterally extending arms 3, 3 journaled on the pin *e* whereby the said frame may occupy an open position as shown in Fig. 4 when it is desired to open the gate *f*, and after the film has been inserted in the projecting apparatus and the gate closed and locked, the frame 1 may be swung into the position shown in Figs. 1, 2 and 3, and locked to the frame *b* in any suitable manner. The locking means shown comprises a set screw 4 threaded in one arm of the fork 5 which is formed in the end of an arm 6 extending laterally from the frame 1, the said fork being adapted to engage the horizontal member *h* of the frame *b*. The shutter frame 1 is provided with upper and lower guards 41 and 42 respectively and an opening 7 which occupies a position directly behind the display opening *c* when the shutter frame is in its closed position. The opening 7 is normally closed by the shutter 8 of any suitable heat resisting material, such as a metal or alloy. This shutter is fixed on and depends from a horizontal rock shaft 9 which is journaled in bearings 10 integral with the frame 1. Upon

the outer end of the shaft 9 is a crank 11 secured by means of a set screw 12. The crank 11 is provided with a recess 13 by which it may be operatively connected with 5 the shutter controlling means 2 which will now be described.

The controlling means 2 is adapted to replace the crank by which the film driving mechanism is ordinarily driven and comprises a sleeve 14 which fits upon and is secured to the usual elongated hub *i* of the large driving gear *j*, the grooves 15 of the said sleeve engaging the keys *k* by which the gear *j* is secured to its hub. A set screw 15^a is provided for locking the sleeve 14 upon the hub *i*. Upon the sleeve 14 and adjacent the shoulder 16 is a friction member 17, preferably in the form of a felt washer. Upon the outer end of the sleeve 14 is 20 mounted a crank member 18 the outer face of which is countersunk as shown at 19 to receive the operating crank 20 having a handle 21 to which the driving power is applied, the crank 20 and member 18 being clamped 25 rigidly together by the bolt 22 and nut 23, the crank accurately fitting the countersunk portion 19, whereby any tendency for the parts to work loose is avoided. An inclined slot 24 is formed in the crank member 18 30 and a pin 25 passes through said slot and is fixed within the sleeve 14. A spiral tension spring 26 is secured at one end to the said pin 25 and at the other end to a support 27 which is rigidly clamped between 35 the nut 23 and crank member 18. The spring 26 normally holds the crank member 18 in the position shown in Fig. 7 wherein the pin 25 bears against the end of the slot 24. The spring is so designed that when 40 driving power is applied to the crank 20 the resistance set up by the film and film driving mechanism will cause the spring to yield, thereby producing a relative movement of the pin 25 and slot 24, that is, a 45 limited spiral movement of the member 18 upon the sleeve 14. Such movement may, however, be prevented if desired by a screw or stop 28 which is threaded in the end of the crank 20. When this stop abuts against 50 the end of the sleeve 14 as shown in Fig. 5, no movement of the member 18, with respect to the sleeve 14 can take place, but by moving the stop 28 outward the spiral movement referred to will be permitted. 55 The crank member 18 is preferably of metal and its inner face 29 may be covered by a washer 30 of comparatively soft material such as fiber, secured thereto by countersunk screws 31. Loosely mounted upon the 60 sleeve 14, between the washers 17 and 30, is a ring 32 which may be of metal, such as steel, and which is provided with an ear 33 to which is pivoted at 34 a link 35 which forms an operating connection between the 65 ring 32 and crank 11, a pin 36 being se-

cured to the upper end of the said link and adapted to engage the recess 13 in said crank.

The operation of the device is as follows: The film having been threaded through the apparatus and the parts being in the position shown in Figs. 1 and 3, the operator grasps the handle 21 and applies driving power to the crank 20; the resistance set up by the film and film driving sprockets and gears causes the crank member 18 to be 70 moved spirally with respect to the sleeve 14 by reason of the engagement of the inclined slot 24 and pin 25, such movement of the crank 20 being indicated by the dotted lines in Fig. 3. This movement causes the washer 30 to press the ring 32 against the felt washer 17, and as the crank 20 is rotated by the operator the friction developed between the felt washer and the ring 32 causes the latter to turn from the position of Fig. 3 to that 75 shown in Fig. 2, thereby through the link 35 and crank 11 turning the rock shaft 9 and elevating the shutter 8 into the position of Fig. 2 so that the light for projecting the pictures upon the film may reach the display opening *c*. As soon as the driving power is removed from the crank 20, the spring 26 will restore the crank member 18 to its original position thereby removing the pressure of the ring 32 upon the friction 80 member 17, and the weight of the shutter 8, crank 11, and link 35 will cause the shutter to close, thereby cutting off the projecting light from the film. In case, however, the operator wishes to pass a film 85 through the apparatus without opening the shutter, all that is necessary to do is to turn the screw 28 until it presses against the end of the sleeve 14, as shown in Fig. 5, and the film may then be driven at any speed while 90 the shutter remains closed.

Having now described my invention, what I claim as new and desire to secure by Letters Patent is as follows:

1. In a kinetoscope, the combination of a 110 frame having a display opening, driving means for passing a film across said opening, a normally closed shutter back of said opening, frictional means for holding said shutter open during the operation of the film driving means and means for rendering said frictional means inoperative, whereby the shutter remains closed during the operation of the film driving means, substantially as set forth.

2. In a kinetoscope, the combination of a 115 frame having a display opening, means for passing a film across said opening, a normally closed shutter back of said opening, a friction member connected to said shutter, 120 and a rotary friction member automatically moved by the driving torque toward the other friction member, substantially as set forth.

3. In a kinetoscope, the combination of a 125

frame having a display opening, means for passing a film across said opening, a normally closed shutter back of said opening, a friction member connected to said shutter, 5 a rotary friction member automatically moved by the driving torque toward the other friction member, and means for restoring said latter friction member to its normal position when the torque is removed, 10 substantially as set forth.

4. In a kinetoscope, the combination of a frame having a display opening, driving means for passing a film across said opening, a normally closed shutter back of said opening, a friction member connected to said opening, a pair of members for transmitting power to said film driving means and connected to each other by a pin and inclined slot connection, and a friction member 15 movable thereby into operative relation to said first named friction member, substantially as set forth.

5. In a kinetoscope, the combination of a frame having a display opening, driving means for passing a film across said opening, a normally closed shutter back of said opening, a friction member connected to said shutter, a pair of members for transmitting power to said film driving means and connected to each other by a pin and inclined slot connection, a friction member movable thereby into operative relation to said first named friction member, and a spring for restoring said power transmitting members 30 to their normal position, substantially as set forth.

6. In a kinetoscope, the combination of a frame having a display opening, driving means for passing a film across said opening, 40 a second frame, a horizontal rock shaft journaled in said second frame and having a depending shutter, and means for turning said rock shaft to hold the shutter open during the operation of the film driving means, substantially as set forth.

7. In a kinetoscope, the combination of a frame having a display opening, means for passing a film across said opening, a shutter frame, a horizontal rock shaft journaled in 50 said frame and having a depending shutter, a recessed crank upon said rock shaft and a link having a pin engaging the recess of said crank for operating the same, substantially as set forth.

8. A driving attachment for kinetoscopes comprising a sleeve provided with means for securing it in driving relation with respect to the kinetoscope driving mechanism, a crank member having a connection with said sleeve permitting a relative spiral movement of said member and sleeve, and adjustable means for preventing said spiral movement, substantially as set forth.

9. A driving attachment for kinetoscopes 60 comprising a sleeve provided with means for

securing it in driving relation with respect to the kinetoscope driving mechanism, a crank member connected to said sleeve by a pin and slot connection, and an adjustable stop carried by said crank member and adapted to abut against the end of said sleeve to prevent relative movement of said pin and slot, substantially as set forth. 70

10. In a kinetoscope, the combination of a frame having an opening, means for moving a film across said opening, a second frame pivoted to said first frame and having an opening in alignment with said first named opening when said second frame is in its closed position, a shutter pivoted to 80 said second frame in such position as to normally register with said openings, a crank connected to said shutter, and means controlled by the film moving mechanism for operating said crank to open said shutter, substantially as set forth.

11. In a kinetoscope, the combination of a frame having an opening, means for moving a film across said opening, a second frame pivoted to said first frame on a vertical axis 90 and having an opening in alignment with said first named opening when said second frame is in its closed position, a shutter pivoted to said second frame in such position as to normally register with the said openings, 95 a crank connected to said shutter, and means controlled by the film moving means for operating said crank to open said shutter, substantially as set forth.

12. A shutter attachment for kinetoscopes 100 having a vertical gate pin comprising a frame adapted to be pivoted on said gate pin, and a rock shaft journaled in said frame and carrying a shutter and a crank, substantially as set forth.

13. In a kinetoscope, the combination of a frame having a light aperture, a main shaft, and film feeding mechanism, a gravity closure for the light aperture having an outwardly extending member, a member loose 110 on the main shaft, and means connected with said last named member for engaging the outwardly extending member of the closure and opening the closure, and holding the same open while the main shaft is in operation, and releasing the closure when the main shaft ceases to operate, substantially as set forth.

14. In a kinetoscope, the combination of a frame having a light aperture, a main shaft, 120 a friction clutch member thereon, a sleeve loose on said shaft, a crank handle adapted to hold the loose sleeve in contact with said clutch member, while the crank is being operated, whereby the sleeve is frictionally connected to the shaft, a hinged closure normally covering the light aperture, and operative connections between the closure and said sleeve, whereby the rotation of the sleeve 125 opens the closure and maintains it open while 130

the crank handle is in operation, said sleeve and its connections moving relative to the shaft and returning to normal position and allowing the closure to cover the light aperture when the crank handle ceases to operate, substantially as set forth.

15. In a picture projecting machine, the combination with the film moving mechanism thereof, of a hinged door, the said door having a sight opening therein, a gravity shutter normally closing said opening, film protecting shields carried by the upper and lower edges of said door, and means actuated by the above mentioned mechanism for raising said shutter, substantially as set forth.

16. A shutter attachment for kinetoscopes comprising a vertically hinged gate frame, and a rock shaft journaled on said frame and carrying a shutter and a crank, substantially as set forth.

17. In apparatus of the class described, a movable screen, a revoluble shaft, mechanism whereby said screen is connected with said shaft, clutching devices by which said mechanism is fixed and unfixed in relation to said shaft, a sleeve movable longitudinally in relation to said shaft to engage and disengage said clutching devices, a handle, and means whereby said handle revolves said shaft and moves said sleeve longitudinally, substantially as set forth.

18. In a kinetoscope, the combination of a frame having a display opening, means for passing a film across said opening, a normally closed shutter back of said opening, a friction member connected to said shutter, a rotary friction member adapted to coöperate with said first named friction member for moving the shutter, and means controlled by the driving resistance for causing said friction members to be brought into operative relation with respect to each other, substantially as set forth.

19. In a kinetoscope, the combination of a frame having a display opening, means for passing a film across said opening, a normally closed shutter back of said opening, a friction member connected to said shutter, and a rotary friction member automatically pressed against the other friction member by the driving resistance or torque, substantially as set forth.

20. In a kinetoscope, a frame having an opening and means for passing a film across said opening, said means comprising a shaft and a crank member having limited spiral movement with respect thereto, and adjustable means for preventing said spiral movement, substantially as set forth.

21. In a kinetoscope, the combination of a frame having an opening, means for moving a film across said opening, a gate pivoted to said frame, means for locking said gate in closed position with respect to said frame, a shutter-carrying frame pivoted to

said first frame on an axis which coincides with the axis of said gate and having an opening in alinement with said first named opening when the shutter-carrying frame is in its closed position, a movable shutter mounted on said second frame in such position as to normally register with said opening, shutter actuating means, and means controlled by the film moving means for operating said shutter actuating means to open said shutter, substantially as set forth.

22. In a kinetoscope, the combination of a frame having an opening, means for moving a film across said opening, a second frame pivoted to said first frame and having an opening in alinement with said first named opening when said second frame is in its closed position, a movable shutter mounted on said second frame in such position as to normally register with said openings, a lever for opening said shutter, and means controlled by the film moving means for operating the said lever, substantially as set forth.

23. In a kinetoscope, a frame having a light aperture, a main shaft and film feeding mechanism, a movable closure for such aperture, a driving member movable longitudinally on said shaft when turned and mechanism between said closure and said shaft engaged by said member in its longitudinal movement to open said closure, substantially as set forth.

24. In a kinetoscope, a frame having a light aperture, a main shaft and film feeding mechanism, a movable closure for said aperture, a driving member on said shaft movable longitudinally thereof into normal driving position, and connections between said closure and said member operatively engaged by said member to hold said closure open when said member is in normal driving position, substantially as set forth.

25. In a kinetoscope, the combination of a frame having a display opening, means for passing a film across said opening, a normally closed shutter back of said opening, a member operatively connected to said shutter and means comprising a rotary member pressed automatically against the first named member to open the shutter by the driving resistance or torque, substantially as set forth.

26. In a motion picture machine, a frame having a projection aperture, a main shaft and film feeding mechanism, a movable closure for such aperture, a driving means connected with said shaft by means permitting a limited relative movement thereof, and mechanism between said closure and said shaft directly engaged by said member at one limit of such relative movement to open said closure, substantially as described.

27. In a motion picture machine, a frame having a projection aperture, a main shaft

and film feeding mechanism, a movable closure for such aperture, a driving member mounted on said shaft and movable for a limited distance with respect thereto when turned, and a member operatively connected to said closure and loosely mounted on said shaft, said driving member in such relative movement operatively engaging said second named member to effect turning movement

thereof about the axis of the shaft to open 10 the shutter, substantially as described.

This specification signed and witnessed this 20 day of April 1906.
